UNITED STATES PATENT OFFICE

REWARD H. DAVENPORT AND JAMES PORTER, OF SOUTH JACKSONVILLE, FLORIDA

RAILWAY-CAR-TRUCK SIDE FRAME

Application filed September 26, 1927, Serial No. 222,090. Renewed November 4, 1929.

This invention relates to side frames for railway car trucks, and is more particularly concerned with the construction and arrangement of the journal boxes positioned at the ends of the side frames.

One of the problems concerned in the construction and arrangement of such side frames has been a construction of journal box housing and support which will facilitate the bodily removal of wheels and axles with their journal boxes without weakening the box housing and supporting structure, and without involving the use of numerous removable parts subject to corrosion, rust, wear and loose connection, and requiring a substantial outlay in time for their insertion and removal even when not "frozen" on through rust.

As previously practised or proposed, the housings for the end journal boxes of the side frames have been formed as sections or in separable portions involving the application and removal of heavy bolts to assemble or close, or to disassemble or open their housings. Such constructions, also, have not been such as to make it possible to jack up the side frame and car body to relieve the weight on the wheels and axles, and permit their removal except through the use of heavy jack equipment not always available. The ordinary journal jack, which is part of the repair equipment of most trains, is not sufficiently powerful to lift the frame and car the necessary height.

An object of the present invention is to provide in combination with such car side frames, a construction and arrangement of journal box housing which dispenses with the use of the numerous heavy bolts and pins previously used; which is practical and relatively inexpensive to manufacture; which does not sacrifice supporting strength for convenience in operation, but, if anything, increases it; and which will greatly facilitate the removal of the car wheels and axles with

their boxes and enable this to be effected through the use of the ordinary journal jack equipment.

It should be stated that in the removal of the wheel axles and their boxes from the ends of the side frames as previously constructed or proposed, and as proposed herein, jacks are placed under the side frames adjacent to the journal and are operated to engage the frames sufficiently to take the supporting strain off the wheels and axles, whereupon the journal box housings are disassembled or unjointed, and the wheels and axles bodily removed therefrom lengthwise of the car and side frame.

In the accompanying drawings forming part hereof, the invention is illustrated in connection with a truck side frame such as used in standard and ordinary rolling stock, the frame in the preferable embodiment of the invention illustrated, being a drop frame with central bolster and bolster springs and triangular side webbing. Provided at their upper ends are offset under-slung right angular plates bracing the webbing and forming one side of the housing for the end journal boxes, as well as an abutment for the journal jack, this structural feature constituting part of the present invention as will be later apparent.

Reference is had to the accompanying drawings illustrating a preferable embodiment of this invention in connection with a side frame of this character, in which drawings:—

Figure 1 is a side elevation of a side frame mounting wheels and axle bosses housed and supported in end housing boxes constructed in accordance with the present invention.

Figure 2 is an elevation of the same equipment with the box housing completely dropped, the journal box jack supporting that end of the side frame, with the wheel and axle box in position for bodily lateral movement away from the frame.

Figure 3 is a fragmentary vertical section through the end of the frame journal box, the locking lever for its hinged section being shown raised.

5 Figure 4 is a top plan view of the same parts of the lever fully closed and locked by cotter pin.

10 Figure 5 is a detail of the hinged section of the axle boss housing in association with two members of its locking means detached.

15 Figure 6 is a detail of the axle box.

20 Referring to the drawings by numerals, 1 indicates, generically, a truck side frame of standard construction, such as is used largely on freight car rolling stock, this frame being a drop frame with a rectangular central portion 2 joined at its opposite sides by triangular webbing 3 to terminate in the end housing for the axle boxes, with the construction of which, this invention is more particularly concerned. The central rectangular portion 2 comprises a bolster spring-seat 4 and houses the bolster springs 5 and the bolster 6 resting thereon.

25 The triangular side webbing 3, the outer sides of which incline upwardly from the lower edge of the central portion 2 are provided at their upper ends with triangular offsets formed by angled sides 7 and 8 joined thereto at their ends and constituting a portion of the housing for the axle box, and because of its construction, acting as a reinforcement connecting the axle box housing with the side webbing 3. Since the construction of the axle 30 box housing is similar at each end of the side frame, only one need be described in detail. The under face of the side members 8 at the ends of the side frame are formed with enlargements 9, transversely bored to receive the hinge pin of the housing section later to be described. At a point above the enlargement 9, the upper face of the webbing 3 of the frame is provided with spaced ears 10 having alined openings 11 drilled therethrough to receive a latch locking pin. The upper plate 35 of the frame 1 is extended beyond the upper terminal of the triangular side webs 3, forming an overhanging plate or shelf 12 constituting a top member of the axle box housing, one side member of which is formed by the plate 7. The transverse upper edge of the extremity of the shelf or plate 12 which is integral or rigidly connected with the side webbing 3 and frame 1, is bevelled at an angle, as 40 at 13, which may conveniently approximate 45° to provide a thrust receiving and transmitting abutment engaged by the swinging side and bottom sections of the axle box housing. This section, best visualized in Figures 45 2 and 5, may be cast, pressed or otherwise formed as a unitary structure of substantially L-shaped configuration, providing an outer side plate 14 and a bottom plate 15 for the axle box housing, these plates being reinforced and strengthened by edge ribbing 16.

The rear end of the bottom plate 15 is formed with spaced ears 17 drilled in alinement and reinforced by bosses 18, these ears embracing the drilled enlargement 9 on the bottom face of the plate 8 and being hingedly connected thereto by a bolt 19 of substantial strength. The upper end of the side wall 14, as best seen in Figure 5, is enlarged and provided with a lateral bore 20 with which the alined bores 21 in ears 22, formed at one end of a connecting link 23 aline and are pivotally connected through a suitable pivot pin 24. The inner edge of the bored enlargement of the top of the side plate 14 is bevelled as at 25 to correspond to and engage with the bevelled edge 13 of the top plate 12 of the axle box housing. The link 23, which is formed by spaced side bars 26 connected by webbing 27 adjacent their outer ends which bars are provided with boss-reinforced bores 28 at their inner ends, between which is mounted the hinge lug 30 formed integral with the upper side of a locking plate 31 provided at its outer end with a rounded cam surface 32 which engages against the concaved substantially semi-circular face 33 of a transverse abutment 34 integral with or rigidly secured to the upper face of the shelf or top plate 12. The upper face of the locking plate 31 between its hinge lug 30 and its inner extremity is formed with a transverse key groove 35 and, on its under face adjacent to its inner end with a transverse notch 36. Depressing the locking plate 31, after first inserting its cam 32 against the convexed face of the abutment, results in 50 bringing the pivot or hinge points of the link 23 with the side plate 14 and with the plate 31 in alinement forming a dead center; it also results in alining the transverse notch 35 with the alined openings 11 in the ears 10 so that a locking pin 37 may be driven through the alined openings 11 seating in the groove 35 and projecting beyond the opposite ear 10. A cotter pin is preferably used to secure the locking pin in position, since it may be easily removed to permit its withdrawal. The cam 32 draws the bevelled surfaces 25 and 13 firmly into engagement and in conjunction with the dead center alinement of the pivot points above referred to and the locking pressure 55 of the latch pin 37 against the locking plate 31, provides a tightly jointed sectional housing which will be free from vibration and lost motion. The supporting strain placed on the car axle and axle box is transmitted through the latching connections to the side frame, which at the point of strain, is braced by the side plates 7 and 8 and by the wide webbing 3. A portion of this supporting strain is also transmitted through 60 the contact of the bevelled surfaces 25 and 13 to the upper portion of the side frame which is adequately braced by the triangular side webbing, and the angled plates 7, 8, 65 70 75 80 85 90 95 100 105 110 115 120 125 130

Thus it will be seen that the side frame is

not weakened by hinging a section of the axle box housing, and that the construction provided adequately braces and absorbs transmitted strain.

5 The half section of the axle box housing provided by the integral hinged side and bottom 14, 15 when unlatched, is dropped upon the hinge pin 19 to clear entirely, the axle box 38 so that the latter, with its axle and 10 wheels may be rolled on the track, or, if broken, pulled laterally from beneath the shelf 12. Before this is attempted, however, a journal box jack, as shown at 39, Figure 2, is placed beneath one of the plates 8 and is 15 raised to engage the plate and take the supporting strain normally received by the side frame from the wheel axle and its box 38, so that the latter may be freely moved away. The point 19, is not only below the bottom 20 line of the area occupied by the axle box 38, but is offset therefrom so that absolute clearance between the axle box and the hinged depending section 14, 15 of its housing is 25 provided. This enables the jack 39 to move the top plate 12 of the housing slightly upwardly so that there is no interference with the withdrawal of the axle and its box either from above or below.

The described construction while representing a preferable embodiment of the invention, is intended to be illustrative rather than restrictive, and it is anticipated that the specific form of the invention may be varied within the spirit of the invention as defined by the 35 appended claims.

What we claim and desire to secure by Letters Patent is:

1. The combination with a car truck side frame having a horizontally disposed top housing plate and a depending rear housing plate at its extremity, of connected front and bottom housing plates hingedly connected as a unit to the rear side housing plate at a point below and rearwardly offset from the housing 40 face thereof, and latching means having pivotal connection with the top of the front housing plate and arranged to engage and be locked to the upper side of the top housing, said plates constituting a housing to enclose 45 and support the journal box of the car axle.

2. A car truck side frame having one extremity provided with top and rear journal housing plates, and having cooperating integrally connected front and bottom housing 55 plates pivotally mounted on the rear housing plate at a point below said plate and rearwardly offset from its housing face, the top portion of said front plate overlying and being supported by said top housing plate, and 60 latching means connecting the top portion of said front plate with the top housing plate rearwardly of its front edge.

3. In a car side frame, a journal box housing at the end thereof comprising stationary 65 abutting top and side housing members rigid

with the frame and connected therewith and braced thereon by an integral angled plate, one side of which forms part of the said housing, and rigidly connected side and bottom housing members hinged to said frame as a unit at a point below the area of the housed journal box, the top of the hinged side member having an offset overlying and supported on the stationary top member, and means for detachably locking said side and top housing 70 members together. 75

4. A car truck side frame having its extremity provided with an upwardly and outwardly inclined side frame member and with a rigid horizontal extension of the top frame member at the junction of the side member therewith, said extension forming the top plate of a journal box housing, a rigid vertical plate abutting and depending from said top plate and forming a side plate of the 80 journal box housing, and a brace extending transversely therefrom and joined to the inclined frame member, unitary side and bottom housing plates hinged at a point below the first named side plate to drop below the 85 horizontal plane of the housed journal box, and latching means hinged to the free end of the hinged side plate and arranged for interlocking engagement with said horizontal extension. 90

5. A car truck side frame having a journal box housing at one end comprising stationary abutting top and side housing plates rigid with the frame end, and complementary side and bottom plates hinged as a unitary structure by the end of the bottom plate to the stationary side plate at a point below the horizontal plane of the housed journal box and means latching the upper end of the hinged side plate to the top plate comprising a concaved abutment on the top plate, a link pivotally connected at one end to the upper end of the hinged side plate, a locking plate hinged to the other end of said link and having a cam seating against the concaved abutment, and means detachably secured to said plate with its cam in locked connection with said abutment. 100

6. A car truck side frame having a journal box housing at one end comprising stationary 105 abutting top and side housing plates rigid with the frame end, and complementary side and bottom plates hinged as a unitary structure by the end of the bottom plate to the stationary side plate at a point below the horizontal plane of the housed journal box and means latching the upper end of the hinged side plate to the top plate, comprising a concaved abutment on the top plate, a link pivotally connected at one end to the upper end 110 of the hinged side plate, a locking plate hinged to the other end of said link and having a cam seating against the concaved abutment, and means detachably secured to hold said plate with its cam in locked connection with said 115 abutment. 120

125

abutment, said means including abutment ears on the top plate having aligned apertures therein, and a key extending through said apertures and overlying and holding down said plate.

5. Signed at Washington, in the District of Columbia, this 23rd day of September, A. D. 1927.

REPARD H. DAVENPORT.
